UNITED STATES PATENT OFFICE.

JOHN BARBERIE, OF BROOKLYN, NEW YORK, ASSIGNOR TO BARBERIE LOCOMOTIVE APPLIANCE COMPANY, OF NEW YORK, N. Y., A CORPORATION OF NEW YORK.

SAFETY APPARATUS FOR LOCOMOTIVES.

SPECIFICATION forming part of Letters Patent No. 772,394, dated October 18, 1904.

Application filed April 29, 1904. Serial No. 205,449. (No model.)

To all whom it may concern:

Be it known that I, JOHN BARBERIE, a citizen of the United States of America, residing at Brooklyn, in the county of Kings and State 5 of New York, have invented certain new and useful Improvements in Safety Apparatus for Locomotives, of which the following is a specification, such as will enable those skilled in the art to which it appertains to make and use 10 the same.

The object of this invention is to provide an improved safety apparatus for locomotives whereby if the engineer thereof fails to see a set signal said locomotive is brought to a 15 standstill and whereby if the engineer sees the signal and for any reason desires to pass it said apparatus may be moved out of operative position, but in so doing sounds an alarm, locks the throttle in a closed position, 20 and indicates the time of such removal, thereby fixing the blame in case of accident, a further object being to provide such an apparatus which when in contact with a set signal permits the escape of the compressed air 25 from the air-brake pipes, but at the same time may enable the engineer to save most of the air in said pipes and without interfering with the usual air-brake apparatus, and which when the brakes of said locomotive are set automatically closes the throttle, thereby saving 30 steam and consequent wear and tear.

The invention is fully described in the following specification, of which the accompanying drawings form a part, in which the 35 separate parts thereof are indicated by suitable reference characters in each of the views, and in which—

Figure 1 is a rear view of a cab of a locomotive equipped with my apparatus; Fig. 2, 40 a section on the line 2 2 of Fig. 1; Fig. 3, an enlarged view of a valve which I employ and taken on the line 3 3 of Fig. 4; Fig. 4, a top view of said valve similar to Fig. 2, but with the parts in a different position; Fig. 5, an enlarged view of that portion of my apparatus 45 which is externally acted upon by a set signal and showing the method of quickly replacing the same if broken; Fig. 6, a similar view

taken at right angles to Fig. 5 and not in section, showing the method employed of attaching or detaching said contact portion; and Fig. 7, an enlarged detail view of part of the apparatus shown in Fig. 1.

In the drawings forming part of this specification I have shown a cab *a* of a locomotive 55 provided with the usual boiler *a*², throttle *a*³, air-brake engineer's valve *a*⁴, and brake-cylinder *a*⁵, said cylinder *a*⁵ being provided with the usual feed-pipe *a*⁶ and the valve *a*⁷ being connected with the train-line pipe *a*⁸, main 60 reservoir-pipe *a*⁹, and exhaust-pipe *a*¹⁰, all in the usual manner.

Mounted upon the throttle *a*³ and in connection with the latch *b* thereof is a toggle-lever *b*², which upon being forced inwardly 65 draws said latch or locking device *b* away from the segmental ratchet *b*³, and upon continuing said pressure said throttle is closed, as will be seen, and directly to the rear of the toggle-lever *b*² and adapted to act thereon is 70 a plate *b*⁴, mounted upon a piston-rod *b*⁵ of a piston *b*⁶, operating in a cylinder *b*⁷, which is connected, by means of a pipe *b*⁸, to the brake-cylinder *a*⁵, so that when the piston *b*⁶ of the brake-cylinder is forced outwardly by the 75 compressed air of the system part of said air passes to the rear of the piston *b*⁶ and forcing the same forwardly releases and closes the throttle, and when the compressed air is exhausted from the brake-cylinder *a*⁵ the air is 80 also exhausted from the cylinder *b*⁷, and the throttle may be again drawn out.

Mounted in one side of the cab *a* is a cylinder *c*, provided with a piston *c*², which is screwed into a vertical pipe *c*³ and to the top 85 of which is detachably secured a frangible cap *c*⁴, which passes without the cab and is adapted to be engaged and destroyed by a semaphore-arm *c*⁵, arranged along the track at any desired point, said cap *c*⁴ being hollow, as 90 shown, and provided with a flange on the bottom thereof resting upon the top of an enlarged portion of the vertical pipe *c*³ and held thereon by means of a metal cap *c*⁶, provided with vertical and inclined slots adapted to engage pins *c*⁷ on the vertical pipe *c*³.

Placed above the cylinder c and around the vertical pipe c^3 is a cylinder d , which is connected with a similar cylinder d^2 , placed thereover, the cylinder d^2 being in communication 5 with the train-line air-pipe a^7 by means of a pipe d^3 , while the cylinder d has no communication with any air-supply, and the vertical pipe c^3 is provided with a slot d^4 , which is normally within the cylinder d^2 , and by this means 10 when the train-line air-pipe a^7 is charged with air the vertical pipe c^3 and cap c^4 are also charged or filled with air under pressure when in their normal position; but if the vertical pipe c^3 be lowered so that the slot d^4 is within 15 the cylinder d it will be seen that the vertical pipe c^3 is out of communication with the train-line air-pipe and the cap c^4 may be removed or replaced without loss of the air in the train-line air-pipe.

20 The piston c^2 is normally held in its uppermost position by means of a strong spring e , and communicating with the cylinder c above the piston c^2 is a pipe e^2 , which communicates with the boiler or steam-supply through a 25 valve e^3 , the lever of said valve having a segmental ratchet e^4 on one side and being also provided with a latch or locking device e^5 , and the segmental ratchet e^4 engages a rack e^6 on a slide-bar e^7 , operating in guides e^8 to the rear 30 of and in line with the throttle a^3 , said throttle being provided with a pin f , which normally passes through openings f^2 in the guides e^8 and f^3 in the slide-bar e^7 , and it will be seen that before the valve e^3 can be operated the 35 throttle a^3 must be closed, and when said valve-handle is operated the slide-bar is moved inwardly and, the openings f^2 and f^3 no longer registering, the pin f cannot pass therethrough and the throttle cannot be drawn out 40 until the valve is again closed.

Connected with the cylinder c at any desired point is a pipe h , with which is connected a whistle h^2 , preferably placed where the fireman can hear it, and in operative connection 45 with the vertical pipe c^3 is a time-retarder h^3 .

When the locomotive is in motion and the parts of my apparatus are in the operative position (shown in Figs. 1 and 2) and a signal c^5 50 is set, the frangible cap c^4 coming in contact with said signal is broken, and this cap and the pipe c^3 being in direct communication with the train-line air-pipe the air under pressure in said train-line air-pipe is allowed to escape 55 and the brakes are set, and when the air under pressure enters the brake-cylinder a^5 part thereof passes to the cylinder b^7 , and, forcing out the piston thereof, as previously described, the throttle is closed, the steam-supply cut off, 60 and the train brought to a standstill.

If the engineer sees the signal and for any reason decides to pass the same, he releases the latch e^5 of the valve e^3 , closes the throttle, and opens the said valve, at which time the 65 steam rushes to the cylinder c , forces down

the piston c^2 thereof, thereby lowering the frangible cap c^4 out of operative position, and at the same time blows the whistle h^2 , thereby warning the fireman that a signal is being passed and indicates the time of such operation on the recorder h^3 , and it will be understood that the diameter of the pipe h is much less than that of the pipe e^2 , thereby permitting the operation of the piston c^2 , and the slide-bar e^7 having been driven inwardly by 70 the operation of the valve e^3 the throttle cannot again be opened until the valve e^3 is closed and the cap c^4 again placed in operative position by the spring e .

If the engineer did not see the signal and the cap c^4 was destroyed and the train stopped, he operates the valve e^3 , which lowers the pipe c^3 so that the slot d^4 therein is within the cylinder d , which prevents the further escape of air from the train-line air-pipe and permits of 80 the insertion of a new cap c^4 by simply turning the cap c^6 and removing the same from the pipe c^3 and returning the same when a new cap c^4 is in position, after which he closes the valve e^3 , and the parts return to their normal position. It will therefore be seen that the train is automatically stopped if the engineer fails to see the set signal, the apparatus warns the fireman, locks the throttle in a closed position, and registers the time of such operation if he 95 decides to pass the signal, and, because of the simplicity of the construction, permits of the rapid and easy substitution of a new frangible cap if one be broken.

My apparatus is simple in construction and 100 operation, well adapted for the purpose for which it is intended, and comparatively inexpensive, and various changes in and modifications of the construction herein shown and described may be made without departing from 105 the spirit of my invention or sacrificing its advantages.

Having fully described my invention, what I claim as new, and desire to secure by Letters Patent, is—

1. In an apparatus of the class described, a closure device in communication with the air-brake pipes of a locomotive, devices for moving said closure device out of operative position and means for preventing loss of air from 115 said pipes when said closure device is removed from its operative position, substantially as shown and described.

2. In an apparatus of the class described, a closure device in communication with the air-brake pipes of a locomotive, devices for moving said closure device out of operative position and means for removing and replacing 120 said closure device without loss of air from said pipes, substantially as shown and described.

3. In an apparatus of the class described, a vertically-movable pipe in communication with the air-brake pipes of a locomotive, a frangible cap on the end of said vertically- 130

movable pipe, an enlarged member on the end of said last-named pipe, a metal cap sliding thereover and between which and said last-named pipe said frangible cap is adapted to be held, lugs on the side of said enlarged member, and vertical and inclined slots in said metal cap engaging said lugs and holding said enlarged member, frangible cap and metal cap together, substantially as shown and described.

4. In a safety apparatus, a vertically-movable pipe in communication with the air-brake pipes of a locomotive, a closure device on the end thereof adapted to be externally struck, a piston on the bottom of said pipe, a cylinder in which said piston operates, a pipe communicating said cylinder with the steam-supply of said locomotive, a valve interposed in said pipe and means for locking said valve, substantially as shown and described.

5. In a safety apparatus for locomotives, a cylinder, a piston therein, a pipe on said piston in communication with the air-brake pipes of said locomotive, a supplemental pipe communicating said cylinder with the steam-supply of said locomotive, a valve in said last-named pipe and a whistle connected with said cylinder, substantially as shown and described.

6. In a safety apparatus for locomotives, a vertical pipe, a closure device on the end thereof, devices at the other end of said pipe for moving the same vertically, a cylinder about said pipe, a supplemental pipe connecting said cylinder with the train-line air-pipe of said locomotive, a supplemental air-tight cylinder below said first-named cylinder and about said vertical pipe, a slot in said vertical pipe communicating with said first-named cylinder, normally, and means for moving said vertical pipe so the said slot communicates with said air-tight cylinder, substantially as shown and described.

7. In a safety apparatus for locomotives, a brake-cylinder in communication with the air-brake system of said locomotive and means connected with said brake-cylinder for closing the throttle of said locomotive when said brake-cylinder is operated, comprising a cylinder, a piston therein, adapted to bear against said throttle and a pipe communicating said cylinder with said brake-cylinder, substantially as shown and described.

8. In a safety apparatus for locomotives, a pipe in communication with the air-brake pipes of said locomotive, a closure device on the outer end thereof and means for removing said closure device from operative position, said means being operative only when the throttle is closed and adapted to lock said throttle in a closed position when said closure device is moved from its operative position, substantially as shown and described.

9. In a safety apparatus for locomotives, a

throttle, air-brakes, a destructible member in communication with the supply-pipes of said air-brakes, devices for locking said throttle when said destructible member is moved from its operative position and means for closing said throttle when said air-brakes are operated, substantially as shown and described.

10. In a safety apparatus for locomotives, a vertical pipe in communication with the air-brake pipes of said locomotive, a frangible cap on the end thereof, a piston and cylinder connected with the other end thereof, a supplemental pipe connecting said cylinder with the steam-supply of said locomotive, a valve in said supplemental pipe, a throttle, a slide adjacent thereto, guides for said slide, openings in said guides registering with each other, through which said pin passes, an opening in said slide registering with said first-named openings when in normal position, devices connected with said valve-handle for operating said slide and means for locking said valve-handle in position, substantially as shown and described.

11. In a safety apparatus for locomotives, a frangible cap in communication with the air-brake pipes of said locomotive, devices connected with the steam-supply of said locomotive for moving said cap from its operative position, a time-recorder in operative connection with said cap, a spring keeping said cap normally in operative position, a whistle indicating when said cap is out of its normal position, an external signal for destroying said frangible cap and thereby setting said air-brakes and means for closing said throttle when said air-brakes are operated, substantially as shown and described.

12. In a safety apparatus for locomotives, an air-tight cylinder in communication with the air-brake pipes of said locomotive, a longitudinally-movable pipe therein one end of which is permanently sealed, a closure device on the other end thereof, an opening in said pipe communicating with the air in said cylinder and means for removing said pipe out of communication with said cylinder, substantially as shown and described.

13. In an apparatus of the class described, a throttle, a pin thereon, a slide, guides therefore, openings in said slide and said guides normally registering with each other and through which said pin is adapted to pass, and a valve-handle the operation of which operates said slide, substantially as shown and described.

In testimony that I claim the foregoing as my invention I have signed my name, in presence of the subscribing witnesses, this 28th day of April, 1904.

JOHN BARBERIE.
